(57) **CLAIM**

The ornamental design for a co-axial cable connector, as shown and described.

DESCRIPTION

FIG. 1 is a perspective view of a co-axial cable connector showing my new design;

FIG. 2 is a side elevational view thereof, the other side, top plan and bottom plan views being mirror images;

FIG. 3 is an end elevational view thereof, showing an end on the left side of FIG. 1; and,

FIG. 4 is an end elevational view thereof, showing an end on the right side of FIG. 1.

The broken lines depict environmental structure and form no part of the claimed design.

1 Claim, 4 Drawing Sheets
